Primary Examiner — Bridget L Eland*(74) Attorney, Agent, or Firm* — Marshall, Gerstein & Borun LLP(57) **CLAIM**

The ornamental design for a screen of a display for a hands-free car kit, as shown and described.

DESCRIPTION

FIG. 1 is a front view of a display for a hands-free car kit that has the design;

FIG. 2 is a left-side view of the display for a hands-free car kit; FIG. 3 is a back view thereof;

FIG. 4 is a right-side view thereof;

FIG. 5 is a top view thereof;

FIG. 6 is a bottom view thereof; and,

FIG. 7 is a three quarter front, top, and right-side view thereof. The broken lines in the FIG. 3 view immediately adjacent the claimed areas represent the bounds of the claimed design while the "Parrot" trademark owned by Parrot S.A. of Paris, France, illustrated in broken lines, is directed to environment and is for illustrative purposes only; the broken lines form no part of the claimed design.
